MELBOURNE L. CARPENTIER, OF DETROIT, AND JOHN B. MACAULEY, JR., OF GROSSE POINT VILLAGE, MICHIGAN, ASSIGNEES TO CHRYSLER CORPORATION, OF DETROIT, MICHIGAN, A CORPORATION OF DELAWARE

MANIFOLD

Application filed August 22, 1929. Serial No. 387,806.

This invention relates to manifolds for internal combustion engines. The main objects of this invention are to provide an improved construction of manifolding, particularly the intake conduit thereof, for use in conjunction with a down-draft carburetor; to provide a manifold in which a drain sump is provided for collecting the liquid fuel which drains from the walls of the manifold; to provide a manifold in which the fuel connecting sump is provided with an electric vaporizer for vaporizing the excess fuel and to provide an improved control valve for conducting the exhaust gas directly to the exhaust pipe when in one position, and when in another position, to direct the exhaust gases around the intake manifold so as to heat the same.

An illustrative embodiment of this invention is shown in the accompanying drawings in which:

Fig. 1 is a top plan view of the improved manifold with the end portions of the exhaust conduit broken away.

Fig. 2 is a view in front elevation of the same with a portion thereof in section so as to show the interior construction of the intake conduit.

Fig. 3 is a sectional view taken on the line 3—3 of Fig. 1 with a down-draft carburetor shown in position on the intake conduit.

Fig. 4 is a sectional view of the same taken on the line 4—4 of Fig. 1.

Fig. 5 is a sectional view of a modified form of intake conduit showing the adaptation to the structure of an electric vaporizer.

Fig. 6 is a view taken on line 6—6 of Fig. 4 looking in the direction indicated by the arrows.

Fig. 7 is a perspective view of the bypass valve shown in section in Figs. 3 and 4.

In the constructions shown in the drawings, the improved manifold comprises a substantially horizontally disposed intake conduit 6 of tubular construction which is bowed upwardly from the medial part thereof and whose ends are bent inwardly and provided with flanges 7 and 8 which are adapted to be attached to the intake of an internal combustion engine 9. A substantially vertically dis-

posed conduit 10, also of tubular construction, is integrally formed on the top medial part of the conduit 6 with the lower end thereof 11 communicating with the conduit 6. The top end of the conduit 10 is provided with a laterally extending flange 12 which is adapted to receive and support a down-draft carburetor 13.

The inside lower wall of the conduit 6, at a point directly beneath the lower end of the conduit 10, is provided with a shallow depression 14 which serves as a collecting sump for liquid fuel which drains from the walls of the intake conduits. A discharge outlet 15 provides communication between the sump 14 and the outside atmosphere, a drain pipe 16 being provided on the lower end of the discharge outlet 15 for conducting the fuel away from the carburetor and to a point preferably beneath the dust pans usually provided along the sides of the engine.

The medial part of the intake conduit 6 has a housing 17 integrally formed therearound, and in spaced relation thereto, so as to provide a passageway 18 which extends transversely to the axis of the conduit 6 and which is open on the inner face thereof above and below said conduit. The inner face of the conduit 6, on that portion thereof within the housing 17, is provided with an axially extending rib 19, the face of which is flush with the faces 20 and 21 of the housing 17; that is, these faces are all in the same plane.

An exhaust conduit 22 is provided inwardly toward the engine from the housing 17 and the medial part of said exhaust manifold is provided with a depending portion 23, the lower end of which is provided with a laterally extending flange 24 to which an exhaust pipe 25 is secured by means of cap screws 26 and 27.

The outer face of the depending portion 23 of the exhaust conduit is adapted to register with, and tightly fit against the faces 20 and 21 of the housing 17, and are secured together by cap screws 23A. A circular opening 28 is provided in this outer side of the exhaust manifold for receiving the outer end of a valve 29, the inner end of which abuts against the inner wall of the portion 23. The

valve 29 is provided with a stem 30 secured rigidly thereto by a pin 31. The stem 30 is journaled in an inwardly extending horizontally disposed tubular boss 32 integrally formed on the inner wall of the depending portion 23 of the exhaust conduit. The end of the valve stem 30 protrudes beyond the outer side of the manifold and is provided with an arm 33 rigidly pinned thereto. The arm 33 has one end of a helical compression spring 34 secured thereto for normally holding the valve in one of its positions. The other end of the helical compression spring 34 is attached to a clip 35 which is secured by a cap screw 36 to a boss 37 formed on the inner side of the manifold. The arm 33 is adapted to have manually operable connections attached thereto for turning it through an arc of 90 degrees so as to move the valve 29 to either of two positions. These manual controls preferably terminate on the instrument board of the vehicle dash.

The valve 29 comprises a head portion 38 on the outer face of which is integrally formed an outwardly projecting fin 39, which extends radially on diametrically opposite sides from the valve stem 30. The outer face of the fin 39 fits snugly against the outer face of the rib 19, said faces being parallel to each other when assembled. The head 38 of the valve supports two axially extending skirt portions 40 and 41 which are semi-circular in shape at their terminating ends, said skirt portions being in spaced relation to each other so as to provide a diametrically extending passageway through the valve between the skirts. The skirt portions, inward from their terminating semi-circular ends, slope inwardly toward the axis of the valve stem 30, so that when the fin 39 is horizontal and in registry with the rib 19, communication is provided from the exhaust conduit downwardly and outwardly into the passageway 18 of the housing 17, around the intake conduit 6 and then back underneath the opposite sloping side of the valve skirt as shown by the arrows in Fig. 3 of the drawings. An electric vaporizer 46 is preferably provided in the depression 14 for vaporizing the fuel which accumulates therein.

In the modified construction shown in Fig. 5 of the drawings the sump into which the liquid fuel drains from the walls of the conduits is of greater depth than that shown in the preferable embodiment and forms a combined drain sump and vaporizing chamber 45 and into the bottom of which is threaded an electric vaporizer 46. The vaporizer 46 has a binding post 47 on the lower exterior end to which suitable electric wiring may be secured. The side wall of the sump 45, at a point spaced upwardly from the bottom, is provided with a discharge outlet 48 which limits the amount of fuel which may accumulate in the drain sump.

In the operation of this manifold, it is secured to the side of an internal combustion engine in the usual manner and the down-draft carburetor 13 mounted on the upper end of the intake conduit 10. When the motor is cold and is first turned over to start, some of the fuel vapor is condensed on the side walls of the conduits 10 and 6. This condensed fuel drains into the collecting sump 14, due to the upwardly bowed ends of the conduit 6, and is discharged from said sump through the outlet 15 and pipe 16 so that the engine does not become choked and clogged with an excess of raw gas.

In order to facilitate and speed up the heating of the intake conduits, the valve 29 is turned to the position shown in Fig. 3 of the drawings so as to cause the exhaust gases to pass out through the side of the exhaust manifold into the passageway 18 of the housing 17, thence around the conduit 6 and then back to the exhaust pipe 25.

As soon as the intake conduits have been heated up, the valve 29 is rotated one quarter turn to the position shown in Fig. 4 of the drawings. When in such position the head of the valve closes the opening into the passageway 18 and the exhaust gases pass directly downward between the spaced skirts of the valve into the exhaust pipe 25 as shown by the arrows in Fig. 4.

In the modified form shown in Fig. 5 of the drawings, the excess condensed fuel drains into the chamber 45 until it rises to the level of the discharge outlet 48. The electric vaporizer 46 is connected to the electric circuit of the car and the action of the vaporizer quickly heats up and vaporizes the fuel collected in the bottom of the sump.

Although but one specific embodiment and one modification of this invention have been shown and described, it will be understood that numerous details of the construction shown may be altered or omitted without departing from the spirit of this invention, as defined by the following claims.

We claim:

1. A manifold for an internal combustion engine comprising a conduit adapted to be attached to the intake of the engine and having end portions bowed upwardly slightly from its medial part, an upright conduit having its lower end communicating with said first mentioned conduit and its upper end adapted to support a down-draft carburetor, said first mentioned conduit having a depression in the inner surface of the lower side wall of its medial part for receiving liquid fuel drained from the walls of said conduits and a discharge outlet for draining the liquid from said depression.

2. A manifold for an internal combustion engine comprising a substantially horizontally disposed conduit having slightly upwardly inclined end portions adapted to be

- attached to the intake of the engine, a substantially vertically disposed conduit having its lower end communicating with said first mentioned conduit and its upper end 5 adapted to support a down-draft carbureter, said first mentioned conduit having a depression in the inner surface of the lower side wall thereof for receiving liquid fuel drained from the walls of said conduits and a discharge outlet providing communication between said depression and the outside atmosphere for draining the liquid from said depression. 10
3. A manifold for an internal combustion engine comprising a substantially horizontally disposed conduit having its ends adapted to be attached to the intake of the engine, the respectively opposite end portions of said conduit being bowed upwardly from the medial part thereof, a substantially vertically disposed conduit having its lower end communicating with the medial part of said first mentioned conduit and its upper end adapted to support a down-draft carbureter, said first mentioned conduit having a depression in the lower inside wall thereof for receiving liquid fuel draining from the walls of said conduits and a discharge outlet for draining the liquid from said depression. 15
- 30 4. A manifold for an internal combustion engine comprising a substantially horizontally disposed conduit having end portions bowed upwardly from the medial part thereof, a substantially vertically disposed conduit having its lower end communicating with said first mentioned conduit at the medial top side thereof for supporting a down-draft carbureter on the upper end thereof, the lower inside wall of the medial part of said first mentioned conduit having a depression therein at the inner extremities of the bowed portions of the conduit for receiving liquid fuel draining from the walls of said conduits and a discharge outlet providing 20 communication between said depression and the outside atmosphere for draining the liquid from said depression. 25
5. A manifold for an internal combustion engine comprising a substantially horizontally disposed conduit adapted to be attached to the intake of the engine, a substantially vertically disposed conduit having its lower end communicating with said first mentioned conduit and its upper end adapted to support a down-draft carbureter, said first mentioned conduit having a depression in the lower inside wall thereof for receiving liquid fuel draining from the walls of said conduits and an electric vaporizer in said depression for vaporizing the liquid fuel therein. 30
6. A manifold for an internal combustion engine comprising a substantially horizontally disposed conduit having its ends adapted to be attached to the intake of the engine, said conduit being bowed upwardly from the medial part thereof, a substantially vertically disposed conduit having its lower end communicating with the medial part of said first mentioned conduit and its upper end adapted to support a down-draft carbureter, said first mentioned conduit having a depression in the lower inside wall thereof in registration with the outlet of the vertically disposed conduit for receiving liquid fuel draining from the walls of said conduits, and an electric vaporizer in said depression for vaporizing the liquid fuel therein. 35
7. A manifold for an internal combustion engine comprising a substantially horizontally disposed conduit adapted to be attached to the intake of the engine, a substantially vertically disposed conduit having its lower end communicating with said first mentioned conduit and its upper end adapted to support a down-draft carbureter, said first mentioned conduit having a depression in the lower inside wall thereof for receiving liquid fuel draining from the walls of said conduits, an electric vaporizer in said depression for vaporizing the liquid fuel therein, and a discharge outlet spaced from the bottom of said depression for limiting the depth of liquid in said depression. 40
8. A manifold for an internal combustion engine comprising a substantially horizontally disposed conduit having its ends adapted to be attached to the intake of the engine, said conduit being bowed upwardly from the medial part thereof, a substantially vertically disposed conduit having its lower end communicating with the medial part of said first mentioned conduit and its upper end adapted to support a down-draft carbureter, said first mentioned conduit having a depression in the lower inside wall thereof for receiving liquid fuel draining from the walls of said conduits, an electric vaporizer in said depression for vaporizing the liquid fuel therein, and a discharge outlet spaced from the bottom of said depression for limiting the depth of liquid in said depression. 45
9. A manifold for an internal combustion engine comprising a substantially horizontally disposed conduit adapted to be attached to the intake of the engine, a substantially vertically disposed conduit having its lower end communicating with said first mentioned conduit and its upper end adapted to support a down-draft carbureter, said first mentioned conduit having a depression in the lower inside wall thereof disposed directly beneath the outlet of said vertically extending conduit for receiving liquid fuel drained from the walls of said conduits and a discharge outlet for draining the liquid from said depression. 50
10. A manifold for an internal combustion engine comprising a conduit for exhaust gases, a fuel intake conduit adjacent said exhaust conduit, a housing surrounding said in- 55

- take conduit in spaced relation thereto providing a passageway extending transversely to the axis of said conduit, an exhaust pipe communicating with said exhaust conduit and 5 a valve between said exhaust conduit and said exhaust pipe movable to two positions and including a cup-shaped member having a diametric passage and diametrically spaced inclined side portions, said valve when in one 10 position losing communication to said housing passageway and providing direct communication through said passage between said exhaust conduit and exhaust pipe, and when in the other position closing direct communication between said exhaust conduit and exhaust pipe and establishing communication therebetween through said housing passageway around said intake conduit.
11. A manifold for an internal combustion engine comprising a conduit for exhaust gases, a fuel intake conduit adjacent said exhaust conduit, a housing surrounding said intake conduit in spaced relation thereto providing a passageway extending transversely 20 to the axis of said conduit, an exhaust pipe communicating with said exhaust conduit and a valve between said exhaust conduit and said exhaust pipe comprising a head, a pair of skirts on said head in spaced relation to each 25 other, the terminating edges of said skirts being semi-circular in shape with respect to the axis of said head, the walls of said skirts sloping inwardly from their terminating semi-circular edges toward the axis of said 30 head, said valve being movable to two positions, said valve when in one position closing communication to said housing passageway and providing direct communication between said exhaust conduit and exhaust pipe 35 between said spaced skirts, and when in the other position closing direct communication between said exhaust conduit and exhaust pipe and establishing communication therebetween through said housing passageway 40 around said intake conduit.
